UNITED STATES PATENT OFFICE.

ROBERT MANDELBAUM, OF BROOKLYN, NEW YORK.

FLASH-LIGHT KEY SAFE.

Application filed August 11, 1925. Serial No. 49,538.

The main object of this invention is to provide a device which serves to make it more convenient for a person to unlock a door in the dark. The invention combines a flashlight and a compartment in which keys are adapted to be stored, the flashlight being selectively illuminated when desired. Persons opening doors with keys late at night often have some difficulty, owing to the keys being stored in the pockets on various positions of the body and a hunt for the keys is necessary, after which additional difficulty is encountered in opening the door, due to the darkness. This invention provides means to illuminate the key hole of a door and at the same time serves as a safe for the keys, which may be opened and held at an advantageous position in front of the lock of the door, the key removed therefrom, and inserted into its place in the lock, this entire operation being accomplished while the lock of the door is illuminated.

The above and other objects will become apparent in the description below, in which characters of reference refer to like-named parts in the drawing.

Referring briefly to the drawing, Figure 1 is a front elevational view of the combination flashlight and key safe when in sealed position.

Figure 2 is a front elevational view, showing the door in partly opened position to expose the keys.

vational view, taken on line 4-4 of Figure 1.

Figure 5 is a bottom plan view of Figure 1.

Referring in detail to the drawing, the numeral 10 indicates an elongated hollow body or casing having semicircular ends 11 and 12. This casing is closed at the top by a roof 13 in which a threaded sleeve 14 is permanently fitted. The sleeve is adapted to receive the threaded socket 15 of a filament lamp 16. The bottom of the casing is closed by a door 17 which is hinged at 18 on the lower side of the semi-circular portion 12 and is adapted to swing downwardly from this hinge axis. The opposite end of the door has a resilient clip 19 formed thereon which is adapted to engage an outwardly projecting ridge 20 formed on the side 10 of the casing, the cooperation of the

ridge and the clip when interlocked, being adapted to retain the door 17 in closed position. On one side of the casing, a rectangular dished-out portion is provided to form an open chamber 21 by the provision of side walls 22 and a floor 23, the side walls and floor being an integral part of the casing and pressed or formed from the same member or material. At the corners where the walls 22 of the dished-out chamber 21 join the remainder of the casing 10, the edge is formed into longitudinal grooves having inclined sides into which the edges 24 also provided with inclined sides, of a slide door 25, are adapted to register. This slide door is of such a length as to close and cover the entire chamber 21 and may be slid longitudinally from place by gripping a finger ledge 26 provided at the lower end of the door 25. In order to permit the door 25 to be slid outwardly to uncover the chamber 21 without disturbing the closed position of the hinged door 17, a recess 27 is formed on the latter door which permits independent movement of the slide door 25 past the cross section of the hinge door 17. Below the chamber 21, an additional chamber 28 is provided. This chamber 28 is adapted to receive an electrical cell 29 which is retained in place in the chamber by the hinged door 17. The terminals of the cell 29 are locked at the upper end thereof and the circuit between the filament lamp 16 and the terminals of the cell 29 are closed by a switch 30 located on the side 12 of the casing 10.

The device is used by holding the casing 10 when the person is right handed, in the left hand. The filament lamp 16 is adapted to illuminate a door lock or area surrounding the key hole of a door lock. The casing is held so that the slide door 25 is at the top of the device. The switch 30 is then manipulated to close the circuit thru the filament lamp and cell 29 and thereafter the slide door 25 is pulled outwardly so that the chamber 21 is exposed. Either of the keys 31 desired for opening the door is then extracted or removed from the chamber 21, after which the key may be inserted into the lock and the door conveniently opened.

I claim:—

A key safe comprising a hollow casing having a lamp bulb at its front end, said casing having a pair of chambers one chamber opening on the side, the remaining chamber

opening at the bottom of said casing, the chamber opening at the bottom being adapted to receive a battery cell therein, means for energizing the lamp bulb from said cell, 5 the chamber opening at the sides having dove-tailed grooves extending longitudinally at the edges of the chamber walls, a slide door having inclined edges registering in said grooves, a hinged door covering the bottom of the casing, said hinged door hav- ing a recess on its side, said recess being adapted to cooperate with the sliding door to permit removal of said slide door from the casing without disturbing the hinged door, said doors being mounted in position 15 of mutual abutment.

In testimony whereof I affix my signature.

ROBERT MANDELBAUM.
